SEWING MACHINE

Harold J. Le Vesconte, Western Springs, Ill., assignor to Union Special Machine Company, Chicago, Ill., a corporation of Illinois

Application May 21, 1942, Serial No. 443,892

3 Claims. (Cl. 112—18)

This invention relates to sewing machines and more particularly to cup-feed sewing machines such as are used extensively in the production of the long back seams of silk hosiery and the like. It has reference especially to an improved feed cup mounting and drive.

An object of the invention has been to provide a unitary feed cup supporting and driving assembly which is simple and economical to construct and to mount in a machine of the character set forth. The improved form and arrangement of the mechanism is such that a feed cup and its drive may be quickly and easily removed and replaced in the event of breakage or other difficulty.

Another object has been to provide a one-way driving clutch for a feed cup or the like which is capable of high speed operation to impart intermittent movement to the feed cup without overthrow. This is important in the seaming of silk hosiery and the like since it insures uniform and accurate stitching at variable speeds. Toward the end stated, the improved construction is such that the parts subjected to intermittent rotation are reduced to a minimum from the standpoint of mass and moment of inertia. In prior one-way clutches for cup-feed machines it has been the common practice to connect a relatively large and heavy outer drum member or housing to the shaft to be rotated intermittently, while the driving means and means for preventing backward rotation have been mounted within the drum member. This has resulted in frequent overthrowing of the feed cups at high speed. To overcome this, the present invention provides for the splitting of the outer drum member of the clutch unit into upper and lower members, identified with the driving and preventing means, respectively, and the mounting of a smaller, inner member of the unit upon the driven shaft for intermittent operation of the latter.

Other objects, features and advantages of the invention will appear from the detailed description of an illustrative form of the same which will now be given in conjunction with the accompanying drawings, in which:

Fig. I is a view, partly in side elevation and partly in vertical section, showing the upper portion of a sewing machine embodying the invention.

Fig. II is a vertical sectional view through a unit forming the supporting and driving means for one of the feed cups.

Fig. III is a horizontal sectional view along the line III—III of Fig. II, and

Fig. IV is a horizontal sectional view along the line IV—IV of Fig. II, with a portion of a plate member broken away for clearer illustration.

Referring now to the drawings, the invention has been illustrated as applied to a machine of the type disclosed in the patent to Rubel et al. No. 2,043,711, granted June 9, 1936. For a fuller disclosure of the various operating devices and the driving connections therefor, reference may be had to said Rubel patent.

Briefly, the machine comprises a hollow frame 10 adapted to be supported from a table and having a laterally extending, hollow bracket at its upper end which houses the driving means for the feed cups. Within the frame 10 are located the various operating connections from a main drive shaft 11, which extends through the opposite side walls of the frame and is provided on the outside of the same, at one or both ends, with a combined handwheel and belt pulley, not shown. Suitable stitch forming devices are provided, these being driven by appropriate eccentrics, or the like, secured to the shaft 11. They include a needle bar 12, adapted to be reciprocated horizontally in a bearing in the frame, a primary looper 13, adapted to be both reciprocated and oscillated, and a secondary looper 14, adapted to be oscillated. The mounting and connections for driving these stitch forming devices and their mode of operation are fully set forth in said Rubel et al. patent.

For the purpose of feeding the work, such as silk hosiery, to be operated upon by the stitch forming devices, suitable intermittently rotatable feed cups 15 and 16 are provided. These are secured, respectively, to shafts 17 and 18 which depend from the overhanging bracket portion of the frame and are driven, in the manner to be explained, by suitable connections with the main shaft 11. The shaft 17 is journaled within a sleeve 19 carried by a bracket 20 pivotally mounted on the overhanging portion of the frame by means of a rock shaft 21. A universal coupling 22 serves to connect the upper end of the shaft 17 with the lower end of a shaft 23 journaled in a bushing 24 carried by the overhanging portion of the frame. A gear 25 secured to the shaft 23 above the bushing meshes with a similar gear 26 secured to the upper end of the shaft 18 by means of a set screw 27 which passes through the hub 28 of the gear. It will be understood that the axes of the shafts 17 and 18 are preferably disposed in a plane which is at an acute angle to the forward face of the housing as well as to the path of reciprocation of the needle; this is for the purpose set forth in said Rubel et al. patent. It

will also be understood that suitable spring means are provided for urging the pivoted bracket 20 in a counterclockwise direction (Fig. I) to hold the feed cup 15 yieldingly in engagement with the cup 16; cup 15 is thus allowed to yield or shift away from cup 16 in the feeding of work of variable thickness.

Beneath the gear 26 there is mounted for oscillation upon the shaft 18 an upper section 29 of a clutch drum or housing. The clutch drum or housing is completed by a lower section 30 having a downwardly extending sleeve-like portion 31 which provides a bearing for the shaft 18. Portion 31 of the lower section of the housing fits snugly within an opening in a downwardly extending boss 32 integral with the overhanging portion of the frame. A screw 33 passing through the wall of the frame serves to retain the lower section of the clutch drum in desired position. The lower end of the sleeve-like extension 31 is preferably reduced in diameter, as indicated at 34. A collar 35 is secured to the shaft 18 just below the extension 31 and serves to retain the parts in assembled relation. It will be seen that a unitary sub-assembly is formed by the shaft 18, gear 26, clutch drum sections 29 and 30, and the parts enclosed by the latter, which will be presently described. All of these elements are retained on the shaft 18 between the hub 28 of the gear 26 and the collar 35. The arrangement is such that in the production of the machine, the sub-assembly indicated may simply be dropped into place in the boss 32 of the frame and then locked in correct position by the set screw 33. Subsequently the feed cup 16 may be secured, by its set screw, to the lower end of the shaft 18.

Between the sections 29 and 30 of the clutch drum there may be provided a flat plate or disc-like member 36, preferably secured by screws 37 or the like to the upwardly extending flange of section 30. Member 36 may, if desired, be formed in two half sections, as indicated in Fig. IV. It serves to space upper rollers 38 from lower rollers 39 of the clutch. If desired, however, the plate or disc 36 may be omitted and the rollers 38 may simply be permitted to rest directly upon the rollers 39. The relative sliding movements of the rollers 38 and 39 are not great and will therefore not be interfered with. When disc 36 is omitted the vertically extending flange portions of the members 29 and 30 may be extended into engagement with each other, or substantially so. The rollers 38 and 39, as will be understood, serve to provide a one-way clutch connection between the member 29 and an inner member 40 of substantially triangular configuration, as shown in Figs. III and IV. Member 40 is secured to the shaft 18, for rotation therewith, by means of a set screw 41. Springs 42, secured to the member 40 at the several corners thereof, cooperate with the two sets of rollers 38 and 39 to assist in bringing about the proper action. Suitable provisions may be made, as disclosed in the patent to Long et al. No. 1,692,130, granted Nov. 20, 1928, for distributing the wear of the rollers over a substantial portion of the cooperating surfaces of the member 40.

For the oscillation of the member 29, this is provided with a lateral extension 43 (Fig. III) having a ball joint connection at 44 with a strap portion 45 at the end of a connecting rod or link 46. At its opposite end this link is pivotally connected with a pin 47 cooperating with an elongated slot 48 in an arm 49 of a rock member mounted on a shaft 50. The pin 47 is adapted to be clamped in any suitable way at any desired

position along the slot 48. By proper adjustment and setting of the pin 47 in the slot 48, the stroke imparted to the link or pitman 46, and hence to the clutch drum section 29, upon each oscillation of the rock member, may be varied as desired. A downwardly extending arm 51 of the rock member is pivotally connected, by a pin 52, with a pitman 53 having a strap portion surrounding an eccentric 54 secured to the shaft 50.

It will be seen from the foregoing that upon each revolution of the shaft 50, the rock member 49, 51 will be oscillated to impart a reciprocatory movement, of variable stroke, to the link or rod 46. This will produce oscillation of the section 29 of the clutch drum. Upon movement of the latter in one direction, i. e., counter-clockwise (Fig. III), it will simply urge the rollers 38 against the springs 42 and will not cause rotation of the member 40. Turning of the latter at this time will, in fact, be prevented by the action of the rollers 39 which become wedged against the inner periphery of the member 30 and thus effectively prevent counter-clockwise turning of the member 40 (Fig. IV). However, on the movement of the member 29 in its clock-wise direction, the rollers 38 will impart a corresponding movement to the member 40, which is not interfered with by the rollers 39 and the drum section 30.

An important feature of the foregoing construction is that the element of the clutch which is secured to the shaft 18, and is given the intermittent movements in one direction, is of relatively small diameter and light weight and hence has a relatively low moment of inertia. The larger and heavier members of the clutch are the oscillatable section 29 of the drum, which is always under positive control by the eccentric 54, and the stationary, backward rotation preventing lower section 30 of the drum. The danger of overthrow of the shaft 18 is thus reduced to a minimum.

As explained in said Rubel et al. patent, provision is made for distributing lubricant through the hollow of the frame 10, including the overhanging portion of the same. Some of this lubricant will be collected in cup-like recesses 55 formed in the upper surface of the gear 26 and may be delivered through passages 56 into similar recesses 57 in the member 29. From these latter recesses the lubricant may be delivered to the interior of the clutch through passages 58, thus insuring adequate lubrication of the clutch surfaces. Excess lubricant may be returned to the reservoir in the main body of the frame through a discharge opening 59 in the member 30. A spiral groove 60 may be provided to convey a portion of the lubricant to the bearing surfaces between the shaft 18 and the sleeve 31.

While an illustrative form of the invention has been described in considerable detail, it will be understood that numerous changes may be made in the construction and arrangement of the various parts without departing from the general principles and scope of the invention. The terms and expressions used herein have been used as terms of description and not of limitation.

I claim:

1. A drive for sewing machine work feeding means adapted to be supported by the frame of the machine and adapted to be intermittently rotated step by step at high frequency, which comprises a main drive shaft, eccentric means driven at high speed by said shaft, and connections from said eccentric means for operating said work feeding means, said connections in-

cluding a one-way clutch having an outer housing divided transversely of its axis into two sections, one of said sections being directly connected for oscillation by said eccentric means, the other of said sections being held stationary, means within said housing lighter than either of the sections thereof operatively connected by an intermittently driven shaft with said work feeding means and arranged to be driven by said one of said sections upon its movement in one direction and to be held by the other of said sections as said one section is moved in the opposite direction, said stationary section providing a bearing for said intermittently driven shaft, and means secured to said driven shaft at opposite sides of said housing so constructed and arranged that the housing and said means within the same form a unitary assembly with said driven shaft separable as a unit from said frame.

2. A drive for a sewing machine feed cup which comprises a driven shaft on which said cup is mounted, a main drive shaft adapted to be operated at high speed, connections from said drive shaft to said driven shaft for imparting step by step, high frequency, intermittent rotation to the latter, said connections comprising a one-way clutch having a housing divided transversely of its axis into two sections, one of said sections being lighter than the other and being mounted for free oscillation on said driven shaft, a member of lower moment of inertia than said oscil-

latable section secured to said shaft and enclosed by said housing, rollers between said member and said oscillatable section providing a one-way drive therebetween, the other section of said housing providing the sole bearing for said shaft, and rollers between said member and said other section of the housing for preventing rotation of said driven shaft in one direction.

3. A unitary assembly for a machine of the class described which is separable as a unit from said machine and comprises a shaft, a clutch member secured to said shaft, a second clutch member mounted for oscillation on said shaft, means forming a one-way driving connection between said clutch members, a stationary member having a sleeve-like portion providing the sole bearing support for said shaft and having a cup-like portion receiving the first mentioned clutch member and partly enclosing the same, means between said first mentioned clutch member and the cup-like portion of said stationary member for preventing rotation of said shaft in a direction opposite to said one-way drive, said cup-like portion carrying an inwardly extending member for spacing said one-way driving means from said rotation preventing means, and means secured to said shaft adjacent the outer ends of said second clutch member and said stationary member for retaining the recited parts in 30 assembled relation.

HAROLD J. LE VESCONTE.
